(57) **CLAIM**

What is claimed is the ornamental design for a coin spinner toy, as shown and described.

DESCRIPTION

FIG. 1 is a top, front, and right side perspective view of the coin spinner toy;

FIG. 2 is a rear plan view thereof;

FIG. 3 is a front plan view thereof;

FIG. 4 is a left view thereof;

FIG. 5 is a right view thereof;

FIG. 6 is a top plan view thereof; and,

FIG. 7 is a bottom plan view thereof.

The equally spaced broken lines on the top surface of the coin spinner toy are surface ornamentation and form part of the claimed design. The remaining broken lines in the drawings are included for the purpose of illustrating portions of the coin spinner toy that form no part of the claimed design.
